[57] CLAIM

The ornamental design for handset telephone or similar article, as shown and described.

DESCRIPTION

FIG. 1 is a front elevational view of a handset telephone or similar article showing my new design;
FIG. 2 is a right side elevational view thereof;
FIG. 3 is a rear elevational view thereof;
FIG. 4 is a left side elevational view thereof;
FIGS. 5 and 6 are respectively bottom and top plan views thereof; and
FIG. 7 is a front, top and right side perspective view thereof, with its slidable bottom tray extended.
